UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

OVERSEAMING-MACHINE.

1,300,449.

Specification of Letters Patent. Patented Apr. 15, 1919.

Original application filed October 28, 1913, Serial No. 797,778. Divided and this application filed March 30, 1916. Serial No. 87,802.

To all whom it may concern:

Be it known that I, JAMES R. MOFFATT, a citizen of the United States, residing at Chicago, in the county of Cook, State of Illinois, have invented certain new and useful Improvements in Overseaming-Machines, of which the following is a description, reference being had to the accompanying drawings and to the figures of reference marked thereon.

The invention relates to new and useful improvements in sewing machines, and more particularly to the needle bar supporting mechanism for an overseaming machine wherein the stitches are formed about the edges of the fabrics which are supported and fed through the machine in substantially a vertical plane. This application is a division of my co-pending application, Serial No. 797,778, filed October 28, 1913.

In this type of machine, the needle is caused to enter the fabric in substantially a horizontal plane, and a looper enters the needle loop on one side of the fabric and is then raised and carried over the edge of the fabric to the other side thereof where the looper thread loop is positioned for the entrance of the needle on its next stroke.

An object of the invention is to provide means for supporting the needle bar in a machine of the above type so that it may be positively reciprocated with little or no lateral vibration.

In the drawings, which show by way of illustration one embodiment of the invention:

Figure 1 is a vertical sectional view showing a machine having my improvements applied thereto;

Fig. 2 is a vertical sectional view, showing the needle bar with means for supporting and operating the same;

Fig. 3 is a detail, showing in side elevation the supporting lug for the rear end of the needle bar.

I have shown my invention applied to a machine consisting of a main frame or supporting casing 1 on which is mounted a fixed bracket 2, supporting a shaft 3 carrying a feed wheel 4. Also mounted on the frame is a movable bracket 5 carrying a shaft 6 supporting a feed wheel 7. The feed wheels 4 and 7 are so positioned as to engage the fabric to be stitched and support and feed

the same in a vertical plane. The shaft 3 is 55 intermittently driven by suitable operating mechanism, and this shaft, through the gear 8 meshing with the gear 9, drives the shaft 6.

Mounted to reciprocate in bearings 10 and 11 is a needle bar 12 which is provided with a head 13 supporting a needle 14. On the needle bar is a collar 15 which is clamped thereto by suitable screws 16. The collar 15 has a depending lug to which is pivoted a link 17. The link 17 is also pivoted to the upper end of a lever 18 which is pivotally supported on a shaft 19 mounted in the frame or casing 1. Said lever between its ends is provided with a ball stud 20 which is engaged by an eccentric strap 21, and this 70 eccentric strap in turn cooperates with an eccentric 22 on the main shaft 23. As the shaft rotates, the needle bar will be reciprocated back and forth in a substantially horizontal path in the bearings 10 and 11. The 75 bearing 11 is in the form of a sleeve fitting a suitable opening in the front wall of the frame or casing 1, and said sleeve projects rearwardly a considerable distance into the machine. The bearing 10 is mounted in a 80 bracket 24 which is preferably cast integral with the frame or casing 1. Said bearing is split at 25 and a screw 26, passing through the split ends of the bracket, serves to clamp the bearing 10 in place.

From the above, it will be apparent that I have provided a fixed bearing to the rear end of the needle bar and a relatively long projecting bearing sleeve for the front portion of the needle bar and between these 90 bearings the needle bar is provided with its operating devices. These bearings for the needle bar form a very efficient support and prevent the needle bar from lateral vibration, while the operating mechanism consisting of a positive train of connections between the needle bar and the eccentric positively moves the needle back and forth.

Cooperating with the needle is a looper 27 carried by a looper bar 28 which is operated so as to cause the looper to enter the needle loop on one side of the fabric, then rise over the edge of the fabric to the other side thereof where the looper thread loop is positioned for the entrance of the needle on 105 its next stroke. This movement of the looper puts more or less lateral strain on the needle and needle bar but the supporting

bearings above described for the needle bar holds said needle bar so that it reciprocates with little or no lateral vibration.

The distance between the bearings 10 and 5 11 is only slightly greater than the throw of the needle bar, and this further prevents undesirable lateral vibrations in the needle bar through the driving connections which are connected to the needle bar at one side of its center line.

It is obvious that minor changes in the 10 details of construction and the arrangement of parts may be made without departing from the spirit of the invention as set forth 15 in the appended claim.

Having thus described the invention, what is claimed as new is:—

A sewing machine including in combination, a casing, devices for supporting and 20 feeding a fabric in substantially a vertical plane, a needle, a horizontally reciprocating

needle bar, a needle head carried by said needle bar and supporting the needle, a bearing in said casing adjacent the needle head, a laterally projecting lug carried by one of the 25 side walls of said casing, said lug having a bearing sleeve for the inner end of said needle bar, and means connected to said needle bar between its supporting bearings for reciprocating the same, said bearing sleeve carried by the casing being extended inwardly some distance from the inner wall of said casing so that the distance between the supporting bearings for the needle bar is only substantially the stroke of the needle bar. 30 35

In testimony whereof, I affix my signature in the presence of two witnesses.

JAMES R. MOFFATT.
